Apparatus for tying weavers' knots, and commonly referred to as "weavers' knotters" and relates more particularly to knotters of the kind in which a knotting bill rotates between two sides of the apparatus across which the strands to be knotted are laid and which after the knot is tied are drawn clear of and carried away from the knotting bill by an outwardly swinging action of one side of the apparatus.

5 In knotters of the kind referred to it has hitherto been necessary for the operator to check slightly by holding one or more of the strands during the knotting operation, and while this in 10 the ordinary circumstances does not present any serious objection, as the operator merely retains hold of the strands after laying them across the knotter it is convenient for some purposes to be able to operate the knotter without retaining 15 hold of the strands, and this invention has for its object to provide an improved knotter of the swinging-arm type referred to, whereby the need for holding the strands is overcome and which, among other features provides, owing to the 20 automatic holding of the strands more even ends to the knot than is usually obtained when a strand or strands is or are held by the user.

According to this invention apparatus of the kind referred to for tying weavers' knots is provided with two slots on each side of the apparatus, each slot having co-operating with it a clipping or holding member working in conjunction with the knotting bill, whereby the strands are held and released as required during the 25 knotting operation thus avoiding the need for the operator to hold the strands.

The invention is more particularly set forth with reference to the accompanying drawings wherein various views of a weaver's knotter made according to the invention and the sequence of the knotting operations are shown and in which—

Fig. 1 is a plan of a knotter, the swinging arm being at the top.

Fig. 2 is a side elevation looking toward the side opposite to the swinging arm.

Fig. 3 is a side elevation of the swinging arm side.

Fig. 4 is a rear elevation.

Fig. 5 is a front elevation.

Fig. 6 is a partial side elevation similar to Fig. 3 showing a modification.

The knotter as shown in the drawings is carried on a support 10 which is shown broken away, but which has a strap or like handle

WEAVER'S KNOTTER

Norman Cook, Manchester, England

Application October 18, 1933, Serial No. 694,029
In Great Britain October 29, 1932

12 Claims. (Cl. 289—3)

This invention has reference to apparatus for tying weavers' knots, and commonly referred to as "weavers' knotters" and relates more particularly to knotters of the kind in which a knotting bill rotates between two sides of the apparatus across which the strands to be knotted are laid and which after the knot is tied are drawn clear of and carried away from the knotting bill by an outwardly swinging action of one side of the apparatus.

60 In knotters of the kind referred to it has hitherto been necessary for the operator to check slightly by holding one or more of the strands during the knotting operation, and while this in the ordinary circumstances does not present any serious objection, as the operator merely retains hold of the strands after laying them across the knotter it is convenient for some purposes to be able to operate the knotter without retaining 65 hold of the strands, and this invention has for its object to provide an improved knotter of the swinging-arm type referred to, whereby the need for holding the strands is overcome and which, among other features provides, owing to the 70 automatic holding of the strands more even ends to the knot than is usually obtained when a strand or strands is or are held by the user.

75 The quadrant 14 from which the trigger 11 projects, and by which it is operated, has teeth 16 along its edge which engage with a worm 17 on a knotting-bill spindle 18 which is mounted to rotate in the back and front members of the frame 15. At the front of the knotting bill spindle 18 is the knotting-bill which is opened and closed when 80 the spindle is rotated by contact and non-contact of the root 19 of the movable member with the eccentrically arranged opening in a front cross extending arm 20 of the frame 15.

85 A spring 21 anchored at the top against one frame member 13 and given several turns round the screw 12 presses against the underside of the trigger 11 and thus tends to keep it and hence the quadrant also in the position in which the whole apparatus is ready for use, it being understood 90 that the whole of the knotting mechanism is worked by the trigger.

95 Projecting below the pivot screw 12 is a portion of the quadrant which has a slot 22 cut in it, the shape of which is shown in Fig. 2 and also on the 100 quadrant and near the back extremity of this slot 22 is a horn 23 which projects across the apparatus toward the swinging-arm side.

105 Pivotally mounted on a slight rearward extension of the frame member 13 on the side opposite to the swinging-arm is a bell-crank lever, one arm 24 of which has a roller 25 mounted on its inside face which lies in the slot 22, and the other arm 26 of which engages a fork 27 projecting downwardly from a sliding arm 28 mounted to slide on securing screws 29 which secure a fixed side member 30 to the frame 15 and between which members the sliding arm 28 is reciprocated. The fixed side member 30 has near its front end 110 a front slot 31 and a back slot 32 and the sliding

arm 28 also has front and back slots 33 and 34 respectively, and between these slots 33 and 34 an arm 35 rises from the member 28 and crosses in a curve over and behind the knotting-bill toward 5 the swinging arm 36 which is pivoted at 37 at the rear of the frame to swing outwardly, a spring 38 being mounted on the pivot 37 to urge the swinging arm into the normal closed position.

The swinging arm 36, is turned across the front 10 of the knotting bill and has upon it a hood 39 which passes over the knotting bill, and it also has a slot 40 in which a cutting member 41 works and which is actuated by an arm 42 passing through a slot in the front portion of the swinging 15 arm. This arm is pivoted at 43 under the swinging arm so as to swing horizontally and actuates the cutter and the actuation is effected by turning upward the inner end of the arm 42 at 44 where it is engaged by a co-operating portion of 20 the frame and is held when the swinging arm is moved outward.

On the inside of the swinging arm is a slider 45 which has an upwardly projecting portion 46 slightly bent round at the front so that between 25 it and the front portion of the swinging arm a slot 47 is formed.

Projecting upwardly from the screw 43 to which it is conveniently anchored is a spring 48 which though on the swinging arm will be referred to 30 for convenience as a fixed spring, and behind this, and carried on the slider 45 is another spring 49. A slot 50 is thus formed between the two springs and when the slide is moved forward the respective slots 47 and 50 will be closed, and anything 35 lying therein will be nipped.

Alternatively, and as shown in Fig. 6 instead of the springs 48 and 49 on the inside the slider 45 is provided with an upstanding portion which is slotted at 50 to correspond with the slot 50 between the springs 48 and 49 and this slot which is 40 conveniently narrower than that formed between the springs is sufficient to hold the thread without the need for nipping between springs. Either arrangement can be used though the former is preferable when dealing with hard or springing yarns.

The slider 45 is not only adapted to slide, but at its rear end it is adapted also to move slightly up and down the up and down movement at the rear being in fact the movement which pushes it forward. This movement is therefore effected 45 through the co-operation of a pin 51 projecting from a downwardly extending part 52 of the slider 45 which pin projects into the path of a pivoted arm 53, which by means of a roller pin 54 projecting through an opening in the adjacent frame member 13 comes into contact with a cam face on the quadrant, which cam face when the quadrant is moved by the trigger raises the pivoted arm 53 which in turn pushes upward the pin 51, and thus, through the downwardly extending 50 portion 52 of the slider 45 moves the rear of the slider up and the front of it forward.

The downwardly extending part 52 of the slider 45 is also engaged by the horn 23 on the quadrant when the horn is brought up near the 55 end of the operative movement of the quadrant, and as the horn 23 and the part it engages are shaped to co-operate the result of their engagement is to swing the swinging arm outward on its pivot 37.

In operating the knotter, it is taken on the left hand, the knotter illustrated being designed for left hand, which however does not affect the construction or operation, and after the left thumb has been placed on the trigger, the two 70

strands to be knotted are laid across the device.

One strand, i. e. the back strand is passed into the slot 50, across the device behind the arm 35, down the slots 34 and 32 of the slider and fixed side arm respectively. The other strand i. e. the front strand is passed into the slot 47 and into the slots 33 and 31 in the slider and fixed arm respectively, and as it is pulled down into these two slots it is carried over the hood 39 and thus passes underneath the hood and across the knotting bill spindle just behind the bill and in passing from this position to the slots 33 and 31 it is guided into the slot of the cutter at the edge of the inwardly turned front 80 of the swinging arm.

When the two strands are placed in this position they will both lie at the bottom of the slots and also will both lie across the knotting bill spindle uncrossed, the front strand lying nearer 85 to the knotting bill than the back strand. When in this position they can safely be released.

It will be noticed by reference to Fig. 2 that the slots on the slider and on the fixed arm do not coincide and consequently as the strands are 90 drawn through the slots in the slider and the fixed side, they are passed through on an incline as considered in plan, and are not drawn straight across as they are in the open slots on the swinging arm. By this angular disposition there is 95 a certain degree of friction or drag applied to the strands which tends to hold them against sliding or slipping. As soon as the trigger is depressed, the knotting bill begins to rotate in a counter clockwise direction and simultaneously 100 the bell-crank lever arm 26 engaging the fork 27 moves the slider forward. Also at the same time the lever 53 is lifted and presses the pin 51 upward which, through the mechanism already 105 described moves the slider 45 on the inside of 110 the swinging arm and the spring 49 (where this arrangement is used) is pressed against the spring 48 thus nipping the strand lying in the slot 50 and the other strand in the slot 47 is nipped between the projecting portion 46 of the 115 slider and the front face of the swinging arm. Where the springs 48 and 49 are not used, the 120 yarn in the slot 50 is held sufficiently by its friction in the slot.

The strands at the swinging arm side are thus 125 nipped as those at the opposite side have the tension on them slightly relaxed as the slots on that side are aligned.

During the tying of the knot, the nipping pressure on the yarn at the swinging arm side 130 is not relaxed, but at the opposite side the pressure is first relaxed by the slider being moved forward and is then re-applied as the slider is moved backward, and is tightened still more as 135 the slider is moved back to a further extent which movement as will be understood is governed by the shape of the slot 22.

Finally, as the tying is completed continued downward movement of the trigger brings the horn 23 into co-operation with the downwardly 140 extending part 52 of the slider 45, and so forces the swinging arm outwardly, the arm drawing the knot off the knotting bill, and the outward movement of the arm actuating the cutter at the front of the swinging arm and severing the 145 strand which passes through it. The loose end caused by this cutting is the same length or approximately the same length as the end left by the cutting operation of the knotting-bill.

The first complete rotation of the knotting- 150

bill forms a loop of the front strand round the bill, and the back strand which is moved forward by the slider on the fixed side is pulled across the knotting bill spindle into a position just behind the bill. The second complete rotation gives a second loop to the front strand and a first loop to the back strand and as the bill comes up it is opened and cuts the back strand on the fixed side, thus leaving only the front strand passing through the bill cutter and front slot on the fixed side.

As this cutting takes place the swinging arm begins to open and as it opens it draws the looped strands off the bill, which however continues to hold the cut strand over which the others are drawn, and as the swinging arm moves further out the front strand on the fixed side is cut by the cutter on the front thus releasing it from the fixed side and the two knotted strands are held in the slots of the swinging-arm from which they are removed as the clipping members release their hold when the pressure is relaxed.

It will thus be seen that the various strands are held as and when required to conform with the movements of the knotting bill and are also cut as and when required during the progress of the knotting operation.

What I claim as my invention and desire to secure by Letters Patent is:—

38. 1. In a weaver's knotter, the combination of a frame, a support for said frame, a rotatable knotting bill mounted in said frame, an actuating element for revolving said bill, an arm at one side of the knotter pivotally mounted on said frame for lateral swinging movement toward and from the other side of the knotter, means at opposite sides of said bill for guiding and gripping the threads to be tied together, and mechanism for operating said means at both sides of said bill independently of each other and in timed relationship to the movements of said bill.

46. 2. In a weaver's knotter, the combination of a frame, a support for said frame, a rotatable knotting bill mounted in said frame, an actuating element for revolving said bill, an arm at one side of the knotter pivotally mounted on said frame for lateral swinging movement toward and from the other side of the knotter, means at opposite sides of said bill for guiding and gripping the threads to be tied together, and connections arranged to be operated by said actuating element for operating said means to grip the threads at one side of said bill during the first part of the rotation of the bill and to release one of them at a predetermined but later point in the rotation of the bill.

50. 3. In a weaver's knotter, the combination of a frame, a support for said frame, a rotatable knotting bill mounted in said frame, an actuating element for revolving said bill, an arm at one side of the knotter pivotally mounted on said frame for lateral swinging movement toward and from the other side of the knotter, means at one side of said bill for gripping both threads but holding them spaced apart, means at the other side of said bill for gripping one of said threads, and connections between both of said means and said element for utilizing the movement of said element to cause said means to grip the threads and to release them at predetermined points during the knotting operation.

75. 4. In a weaver's knotter, the combination of a frame, a support for said frame, a rotatable knotting bill mounted in said frame, an actuating

ing element for revolving said bill, an arm at one side of the knotter pivotally mounted on said frame for lateral swinging movement toward and from the other side of the knotter, and means arranged to be operated by said element for gripping and releasing the threads as required during the knotting operation to avoid the necessity for holding the threads by hand.

5. In a weaver's knotter, the combination of a frame, a support for said frame, a rotatable knotting bill mounted in said frame, an actuating element for revolving said bill, an arm at one side of the knotter pivotally mounted on said frame for lateral swinging movement toward and from the other side of the knotter, parts carried by said arm to provide two thread guiding slots at one side of the bill, additional parts at the opposite side of the knotter providing two slots, one in front of the other, for guiding said respective threads, means cooperating with said slots to guide the threads in the desired positional relationship to said bill, and connections arranged to be operated by said element for relatively moving the parts at both sides of the knotter for gripping and releasing the threads at the desired points in the knotting operation and for swinging said arm outwardly at substantially the completion of said operation.

6. A knotter according to preceding claim 5, in which the thread clamping means at one side of the knotter includes a reciprocating member mounted on said arm, and that at the other side comprises a side piece at the latter side of the knotter and a slide mounted to reciprocate forward and backward relatively to and immediately beside said side piece, both said side piece and said slide having registering slots to guide the two threads to be united, the connections operated by said element being arranged to reciprocate said member and said slide.

7. In a weaver's knotter, the combination of a frame, a support for said frame, a rotatable knotting bill mounted in said frame, an actuating element for revolving said bill, an arm at one side of the knotter pivotally mounted on said frame for lateral swinging movement toward and from the other side of the knotter, a member movably mounted on said arm and cooperating with a part carried by the arm to clamp one of the threads to be operated upon, additional thread gripping means at the opposite side of the knotter, an internal cam on said element, and connections actuated by said cam for operating said member.

8. In a weaver's knotter, the combination of a frame, a support for said frame, a rotatable knotting bill mounted in said frame, an actuating element for revolving said bill, an arm at one side of the knotter pivotally mounted on said frame for lateral swinging movement toward and from the other side of the knotter, a member movably mounted on said arm and cooperating with a part carried by the arm to clamp one of the threads to be operated upon, additional thread gripping means at the opposite side of the knotter, cams on said element for operating said member to cause it to grip the thread and for subsequently swinging said arm and said member away from the bill, and connections actuated by said element for operating said thread gripping means at the other side of the knotter.

9. In a weaver's knotter, the combination of a frame, a support for said frame, a rotatable knotting bill mounted in said frame, a swinging

quadrant connected with said bill to revolve it, an arm at one side of the knotter mounted on said frame for lateral swinging movement toward and from the bill, a slide carried by said arm and cooperating with another part carried by the arm to clamp one of the threads to be knotted, an internal cam on said quadrant, a lever mounted on said frame closely beside the quadrant, a roll carried by said lever and arranged to be engaged by said cam, and connections through which the movement of said lever produced by said cam is transmitted to said slide to give the slide its thread clamping movement.

10. In a weaver's knotter, the combination of a frame, a support for said frame, a rotatable knotting bill mounted in said frame, a swinging quadrant connected with said bill to revolve it, a side piece rigid with said frame and projecting forward beside the bill, said side piece having two slots therein to receive and guide the strands of thread to be tied together, a slide mounted between said bill and said side piece and closely beside the latter for forward and backward movement, said slide having two thread guiding slots arranged to register with the slots in said side piece in certain positions of the slide, a cam on said quadrant, and a lever arranged to be operated by said cam and associated with said slide to reciprocate it in timed relationship to the 30 rotative movements of said bill.

11. In a weaver's knotter, the combination with a frame, a rotatable knotting bill mounted in

said frame, a swinging quadrant connected with said bill to revolve it, an arm at one side of the knotter mounted on said frame for lateral swinging movement toward and from the bill, a slide carried by said arm and cooperating with another part carried by said arm to clamp one of the threads to be knotted, two cams on said quadrant, and connections between said cams and said slide for causing the cams to operate successively during the movement of the quadrant to give said slide its thread clamping movement.

12. In a weaver's knotter, the combination with a frame, a rotatable knotting bill mounted in said frame, a swinging quadrant connected with said bill to revolve it, an arm at one side of the knotter mounted on said frame for lateral swinging movement toward and from the bill, a slide carried by said arm and cooperating with another part carried by said arm to clamp one of the threads to be knotted, an internal cam on said quadrant, connections between said cam and said slide for causing the first part of the swinging movement of the quadrant to operate through said cam to move said slide toward its thread clamping position, and an external cam 23 on 100 said quadrant arranged to operate on said slide at a later point in the swinging movement of the quadrant to hold the slide in its thread clamping position during at least a portion of the swinging movement of said arm.
